PORTABLE DERRICK

Neligh Clair Coates, Kansas City, Mo.

Application January 9, 1941, Serial No. 373,745

6 Claims. (Cl. 212—61)

This invention relates to improvements in portable derricks and has particular reference to the load handling rotary boom type derrick.

In the operation of positioning portable derricks on elevated platforms, to which it is desired to deliver building material, much difficulty is encountered in moving the derrick to the proper position because of projections on the derrick which must be moved out from the platform before the derrick can be moved upwardly or downwardly to properly engage the supporting platform.

The principal object of the present invention is the provision of portable derrick which overcomes the above objections and one that is provided with a pair of spaced apart runners for resting against the supporting platforms as the derrick is moved vertically therealong.

Another object of the present invention is the provision of a novel platform clamping means operable by a foot lever as the operator positions the derrick on the supporting platform with his hands.

A further object of the invention is the provision of a derrick having a downwardly and inwardly converging track with a platform clamping means adjacent its upper end whereby the derrick may be supported in a substantially vertical position with the clamping means engaging the supporting platform and the tracks engaging a vertically inclined platform brace member.

Another object is the provision of a portable derrick having resilient means for forcing a pair of board clamping members toward each other whereby the derrick is secured to a platform.

Other objects are simplicity and economy of construction, ease and convenience of operation, and adaptability for use in handling various kinds of materials.

With these as well as other objects which will appear during the course of the specification, in view, reference will now be had to the drawings wherein:

Figure 1 is a side elevational view of a portable derrick, shown in operative relation with a platform and embodying this invention.

Fig. 2 is an enlarged horizontal, sectional view taken on line II—II of Fig. 1.

Fig. 3 is an enlarged horizontal, sectional view taken on line III—III of Fig. 1.

Fig. 4 is a front elevation of the derrick in operative relation with supporting platform parts.

Fig. 5 is an enlarged vertical sectional view taken on line V—V of Fig. 1.

Fig. 6 is a side elevation of the derrick positioned with the bar runners resting against the supporting platform as it is being positioned.

Fig. 7 is a fragmentary rear elevational view of the derrick.

Fig. 8 is a side elevational view of a modified form of the derrick having a resilient connecting bar for forcing the clamping members together.

Fig. 9 is an enlarged sectional view taken on line IX—IX of Fig. 8.

Fig. 10 is a modified form of the platform structure wherein the mast adjusting bar is disposed substantially parallel with the supporting floor board and with the adjustable derrick positioned thereon.

Fig. 11 is an end elevation of the structure shown in Fig. 10 with the mast of the derrick shown in a tilted position in solid lines and in the vertical operating position in dotted lines.

Fig. 12 is an enlarged end elevation of the platform adjusting bar and its connecting means to the vertical platform member.

Fig. 13 is a cross sectional view taken on line XII—XII of Fig. 12.

Fig. 14 is a further modification of the platform member wherein the derrick adjusting bar is pivoted at its one end to one of the vertical platform members and adjustable vertically at its free end.

Through the several views of the drawings like reference characters refer to similar parts and the numeral 20 designates a mast shown as a tubular member with a plurality of flat sides, however it may also be made of standard tubular form of any of the various structural shapes, etc. A transversely disposed frame 22, made of sheet metal is welded to the mast 20, intermediate its ends. This frame is substantially triangular in shape with its opposite sides 24 and 26 diverging outwardly from mast 20, and being provided with reinforcing, depending flanges 28. The triangular frame is provided with an opening 30 through which certain parts extend as hereinafter set forth.

Securely attached adjacent each of the outer corners of the frame 20 is a rod 32 which converge downwardly toward each other and toward the mast 20 to form a pair of runners on which the derrick rests for easy adjustment during the positioning operation. These runners also serve to bear against the diagonally dis-

posed tie member 34 positioned to incline vertically at the front side of the platform 36.

Extending outwardly from opposite corners of frame 22 is an arm 38 provided with a depending tine 40 which is adapted to engage the upper surface of floor board 42 of the platform.

A bell crank lever 44 pivoted to bracket 45 depending from frame 22 is pivoted intermediate its ends in such a manner that the outer end portion 46 can be moved to and from a position against the underside of the floor board 42. The other end portion of the bell crank lever is pivotally connected to a connecting bar 48, which has its other end pivotally joined at 49 to an operating bar 50 which in turn is pivoted at 51 to a stationary bracket 52 carried by the mast 20. A link 53 also pivoted at 49 to the operating bar and at 51 to the bracket 52 serves as a reinforcement to prevent undue distortion of the parts.

This operating bar is provided at its free end with a transverse bar 54 and is so positioned and connected with connecting bar 48 that it will move the bell crank lever to a position inside the plane determined by the rods 32 so that the rods will rest against the edge of floor board 42 for free movement from arms 38 to their lower extremities as clearly shown in Fig. 6. When the operating bar 50 is moved downwardly to the position shown in Fig. 1 the lever portion 46 will be forced upwardly against the underside of floor board 42 so that the foot 56 integral therewith will clampingly engage the board to force the tines 40 downwardly into said floor board. It will be noted by referring to Fig. 1 that the operating bar 50 and connecting bar 48 are in angled relation to prevent accidental release of the parts, and that the free end of the operating bar resting on the frame 22 to prevent further movement of the parts.

Reinforcing bars 58 positioned intermediate the frame 22 and the lower end of mast 20 serve to reinforce the runner construction and prevent lateral movement of the mast when in operation.

Due to the fact that it is desirable to vary the distance between arm 38 and the outer end portion of 46 of the bell crank lever it has been deemed advisable to make the connecting bar 48 extensible by providing a turn buckle structure wherein the elongated nut 60 is in threaded relation with the threaded end 62 of connecting bar 48 and the threaded end 64 of section 66 of the connecting bar. The threads are disposed in reverse directions so as to lengthen or shorten the connecting bar by simply rotating nut 60 in the proper direction relative to the bar.

As clearly shown in Fig. 1 a boom 68 is mounted transversely on mast 20 for rotary movement. This boom 68 comprises a frame 70 made of channel irons spaced apart and reinforced by truss rods 72 and provided with a sheave wheel 74 at each of its opposite ends.

A depending spindle 76, see Fig. 5, disposed at a right angle to the axis of the boom extends vertically into socket 78 formed in the upper end of mast 20 to rest on a bearing plate 80 and is secured in axial alignment by the cup portion 82 of the bearing plate and the flanged sleeve 84 which is secured to the underside of boom 68 and extends through opening 69 formed through plate 71 secured to the top end of mast 20. A tubular member 73 is positioned in mast 20 in axial alignment with opening 69 and about the cup shaped portion 82 of the bearing plate 80. The spindle 76 is tapered at its free end for free

movement through opening 69 and into the cup portion 82 of the bearing which is also beveled at 75 to prevent lodgment of the spindle thereon. When the spindle is in the operative position the sleeve 84 is in operative relation with the plate 71 and tube 73 to support the spindle in axial alignment with the mast. This structure permits of easy and rapid positioning of the spindle in the mast 20.

10 A cable 86 secured to the eyelet 88, attached to the boom, extends around the sheave of a block 90 thence over the adjacent sheave wheel 74, lengthwise of the boom, over the opposite sheave wheel 74, thence downwardly to a position for the operator to grasp it from the ground.

15 The modified form shown in Figs. 8 and 9 provides a special connecting bar 100, whereby the bell crank lever will be secured resiliently against the underside of the platform board regardless of the position of the tine 40 in the upper portion of said board.

20 The connecting bar 100 comprises a bar 102 provided with a threaded end portion 104, slidably mounted in a tubular section 106. The outer end of tubular section 106 is bifurcated at 108 to receive the inner end of bell crank lever 44 to which it is pivoted by pin 110. A transverse pin 112 is provided adjacent the lower end member 104, to extend into slots 114 formed through the wall of tubular member 106 to limit the relative movements of the parts. The upper end of bar 102 is pivoted at 49 to the operating bar 50. The upper end of member 106 is preferably flanged at 116 to serve as a bearing for one end of a compression spring 118. The other end of spring 118 rests against a nut 120 threaded on member 104. As shown in Fig. 9 the pin 112 rests against the upper end of slots 114, and the nut is thus adjustable to compress the spring 118 to any desired degree. The amount of compression of spring 118 will be determined by the required force to operate the clamping members to properly engage the floor board 42.

25 It is quite evident that the platform member 34 may be vertically angled to any desired degree from the horizontal and furthermore that due to the angled relation of the runners 32 the platform member 34 might be moved vertically to obtain the proper vertical position of the mast.

30 Referring to Fig. 2 it will be noted that the clamp lever 44 is positioned intermediate arms 38 so that when pressure is applied to the clamping part there will be a tendency to spring the board 40 so that it will have a slight movement to the normal position as the pressure lessens.

35 Referring now to Figs. 10, 11, 12 and 13 wherein is shown a modified form of the platform structure, it will be noted that vertical members 120 support transverse members 122 which carry the platform floor boards 124 thereabove. A suitable longitudinal tie bar 126 is shown to maintain the vertical members in proper relative relation.

40 The derrick, to be used on this platform, is identical with that shown in Fig. 1 and the floor board securing or clamping means engages the outside edge portion of the floor board 124. While the runners 32 are adapted to rest against a vertically adjustable adjusting bar 128. This adjusting bar 128 is detachably secured to the spaced apart vertical platform members 120. The operator may adjust each end of bar 128 vertically to vary the position of the mast as clearly shown in Fig. 11. It will be noted that

when bar 128 is in the lower position as shown in this figure the mast will be inclined from the perpendicular position; however by raising bar 128 to the position shown in dotted lines the mast will be forced to the vertical position with the clamping means engaging the floor board 124.

While substantially any of the various types of adjustable clamping means might be used for securing bar 128 to the upright members 120, however for the purpose of illustration the bar 128 is shown mounted in U-shaped brackets 130 with a rolled upper portion to form an eyelet 132 through which is mounted one leg 134 of a U-shaped member 136. The other leg 138 of member 136 is adapted to engage the opposite side of vertical platform member 120 and is provided with a tine 140 to engage the surface of 120 to prevent slippage of the bar supporting means thereon.

With the bar 128 adjustably mounted in bracket 130 and the member 136 open at its one side, it is quite apparent that this means of supporting the adjusting bar 128 can be quickly and easily attached to any of the ordinary platform structures having vertically disposed supporting members. While it is intended to maintain bar 128 in substantially a horizontal position for the purpose of exerting substantially a light pressure against each of the rods 32 for maintaining the mast in a vertical position, however it is not essential that this adjusting bar be maintained horizontal since it can be adjusted independently at its opposite ends.

The modified view shown in Fig. 1 provides a platform structure identical with that shown in Figs. 10 and 11 and the adjusting bar 140 is shown pivoted by a pin 142 to one of the vertical uprights 120 while the other end extends to bear against the opposite upright member 120 and is supported by a cable 144 attached to the free end of 140 and secured at its other end portion to a hook member 146. When it is desired to adjust the derrick so that the mast is in a vertical position, the operator simply loosens the cable 144 from 146, raises or lowers bar 140 as required and then secures the cable again to 146.

Since in each of the various structures shown the mast is spaced apart from the supporting floor board the weight of the boom and material carried thereby will always cause an inward pressure against the adjusting bar and there will be no tendency for the upper end of the mast to move inwardly above the platform.

In the operation of the derrick it is necessary to move it to the various levels as the building progresses, and for this reason the derrick must be released from one platform and moved to the one placed thereabove. This is accomplished by raising operating bar 50 to release lever 44 to permit free sliding of runners 32 against floor board 42. When the derrick is moved to the upper position it is positioned against the floor board and moved longitudinally thereof so that bars 32 rest against the inclined platform member 34 until the mast 20 is in a substantially vertical position. When thus positioned the operating bar 50 is moved downwardly to secure the gripping members in the gripping position. The clamping means is adjustable to properly engage floor boards of any thickness, however it is evident that the parts of the clamping means are inherently resilient enough to allow some variation in board thickness. As the tine 40 bites deeper into the floor board the lower clamping member

will follow up to constantly contact the underside of said board.

When the vertically adjustable adjusting bars shown in the modified forms are used for positioning the mast it will not be necessary to move the derrick longitudinally of the floor board since the same adjustment may be had by simply adjusting the bars 128 or 140 vertically as described below.

- 10 Since many minor changes might be made in the various parts of this derrick without departing from the spirit of the invention, the broad principles of the invention will be set forth in the appended claims.
- 15 Having thus described the invention, what is claimed as new and desired to be secured by Letters Patent is:
  1. A portable derrick having a mast, an arm rigidly carried by said mast to engage the top side of a floor board of a platform, a pivoted member adapted to engage the lower side of said floor board, means adjustable to resiliently urge said member against the under side of said floor board, and a bar extending downwardly and inclined toward said mast and carried thereby to bear against a vertically inclined platform member for horizontal adjustment therewith whereby said mast is moved to a predetermined operative position.
  2. A portable derrick comprising a mast having an arm rigidly carried by said mast intermediate its ends to engage the top side of a floor board of a platform, a pivoted member carried by said mast adapted to engage the lower side of said floor board, manually operable means adjustable to resiliently urge said member against the under side of said floor board, and a pair of spaced apart, downwardly converging bars rigidly carried by said mast adapted to be adjusted horizontally of and to bear against a vertically inclined platform member of said platform to adjust said mast to a substantially vertical operative position, and a boom rotatably mounted on top of said mast.
  3. A portable derrick comprising a mast, a frame rigidly fixed to and extending, transversely from one side of said mast, a rod extending from each of two spaced apart points of said frame to form runners converging toward and secured to the lower end of said mast, horizontally disposed arms rigidly secured to said frame and having down-turned anchor tines adapted to engage a horizontal platform board, and an adjustable anchor member carried by said frame in offset relation below said arms, and means operable to force said anchor member toward said down-turned anchor tines to securely engage a platform member therebetween.
  4. A portable derrick comprising a mast, a frame extending transversely from one side of said mast intermediate its ends, a pair of spaced apart runners extending from the outer portion of said frame, downwardly toward the lower end of said mast, anchor members extending outwardly from said frame adapted to rest on top of a supporting platform board, an anchor member adjustably carried by said frame below said supporting platform, and means operable to move said lower anchor member upwardly to clampingly engage said platform as said runners rest against an upwardly inclined platform frame member to maintain said mast in a vertical position.
  5. A portable derrick comprising a mast, a frame extending transversely from one side of

said mast, intermediate its ends, a pair of spaced apart runners extending from the outer portion of said frame, downwardly toward the lower end of said mast, anchor members extending outwardly from said frame above said runners adapted to rest on top of a supporting platform board, an anchor member adjustably carried by said frame below said supporting platform, and means operable to move said lower anchor member upwardly to clampingly engage said platform as said runners rest against an upwardly inclined platform member to maintain said mast in a vertical position.

6. A portable derrick comprising a mast, a frame extending transversely from one side of said mast intermediate its ends, a pair of spaced apart runners extending from the outer portion

of said frame, downwardly toward the lower end of said mast, anchor members extending outwardly from said frame adapted to rest on top of a supporting platform board, an anchor member adjustably carried by said frame below said supporting platform, and means operable to move said lower anchor member upwardly toward said upper anchor member to clampingly engage said platform therebetween as said runners rest against an upwardly inclined platform member to maintain said mast in a vertical position, and adjustable means operable to move said lower anchor member any pre-determined distance to securely clamp said derrick to a platform member, and to secure it in said clamped position.

NELIGH CLAIR COATES.
